UNITED STATES PATENT OFFICE

2,449,822

HEAT EXCHANGING APPARATUS

Lauritz Benedictus Schibbye, Essvik, Sweden, assignor to Svenska Cellulosa Aktiebolaget, Stockholm, Sweden, a company of Sweden

Application January 28, 1944, Serial No. 520,090
In Sweden December 11, 1942

1 Claim. (Cl. 257—229)

1

The present invention relates to a heat exchanger of the type in which the mediums between which the heat transfer is to take place, are subjected to helical or spiral motion. As a rule, heat exchangers of this type give a high efficiency, but the embodiments hitherto known have certain inherent disadvantages and limitations. Thus, they are not suitable for mediums which yield deposits in the form of incrustations, soot or the like. They are difficult to repair and the joints and connections are difficult to pack so as to be perfectly tight.

The primary object of the present invention is to provide a heat exchanger of the abovementioned type by means of which these disadvantages are eliminated or at least considerably reduced. A main feature of the invention is that it includes a casing or tube and a body therein, the body having a substantially helical internal passage (or passage system) for one medium and providing a substantially helical external passage (or passage system) for another medium.

An object of the invention is to further improve the heat transfer from one medium to the other by avoiding the double walls in the path along which the heat transfer takes place.

Another object is to provide a large cross-sectional area particularly for the external passage so that a great speed through the exchanger can be given to the medium flowing through the said passage, particularly if it is a gas. This can be done by providing two or more helical ducts and by giving one of the passages a cross-sectional area which is at least twice as large as that of the other.

A further object is to provide a heat exchanger which is easy to disassemble, in order to externally clean the inset body and internally clean the casing or the tube. With such a heat exchanger it is only necessary to avoid the use of a medium which will form deposits in the passage within the inset body.

A further object of the invention is to provide a heat exchanger and an inset body with an internal conduit or conduits, the inset body being formed of a plurality of elements or sections, whereby its manufacture as well as its internal cleaning is considerably facilitated.

Other objects and advantages of the present invention will be more clearly apparent from the following description taken in connection with the accompanying drawings, in which:

Fig. 1 is a longitudinal section of the casing of a heat exchanger embodying the invention, the interior body being shown generally in elevation

2

and comprising three helical or spiral coils threaded one into the other.

Fig. 2 is a section of the apparatus on line II—II of Fig. 1.

Fig. 3 is a longitudinal section of part of another embodiment in which the interior body is a single coil.

Fig. 4 is a similar section of an apparatus with a single coil and of a modified embodiment of the casing or tube.

Fig. 5 is a longitudinal section of a portion of the casing of an embodiment showing the varying pitch and cross-section of the coil.

Referring to Fig. 1, the reference numeral 1 designates a cylindrical, upright casing formed of two halves as will be seen from Fig. 2, and having the detachable cover 2 and the detachable bottom 3. Near its upper end the casing has a flange tube 4 for the connection of a pipe line, and near its lower end there is a similar flange tube 5. The casing encloses three flat hollow coils 6, 7, 8 screwed into one another. The first coil is fixed to an axial center tube 9 forming the core of the coil body, while the other coils 7, 8 are not attached to the center tube and may be screwed into the firstmentioned coil. The three conduits thus obtained are connected to an upper header 13 by means of suitable end portions 10, 11, 12, see also Fig. 2. By means of a neck 14 this header 13 communicates with an opening 15 in the cover 2.

At the bottom the conduits have similar radial end portions 16, 17, 18 connected to a lower header 19 in the casing 1. Through a neck 20 this header 19 communicates with an opening 21 in the bottom 3 and an extra chamber 22 with an opening 23, the said chamber being situated below the said header 19.

The exchanger described operates in the following manner:

One of the mediums participating in the heat exchange is admitted, for example, through the opening 23, passes through the chamber 22 and enters the lower header 19 from which the medium is distributed to the three conduits 6, 7, 8 through the connections 16, 17, 18. Having passed the said conduits the medium, via the connections 10, 11, 12, enters the upper header 13 which thus forms an outlet header for the different medium currents, from which header the collected medium leaves through the opening 15 and a pipe line connected thereto, not shown.

The second medium is admitted for example through the flange tube 4 and thus enters the casing 1 in which the medium passes through the intermediate spaces between the convolutions of the

coils 6, 7, 8. This medium then leaves through the flange tube 5.

Both of the mediums are forced to pass a long distance through the apparatus and in suitably thin layers, and therefore the heat exchange becomes efficient even in an apparatus of moderate dimensions.

In order to clean the apparatus, the two parts of the casing are taken apart after the cover and/or the bottom have been removed.

If desired, the casing may be made up of a plurality of sectional wall elements or parts in such a way that only one or more parts need be removed for the cleaning of the interior of the casing and the exterior of the conduits. The said part or parts may preferably have the form of cleanout openings or manholes. The connection between the header 13 and the cover may be such that the header and the coils can be lifted from the casing by raising the cover.

The cover, the bottom and the remaining parts of the casing may be designed, as to material and thickness thereof, for adequate strength to permit a substantial pressure on the medium flowing through the passage or passages on the outside of the inset body, and the pressure on the medium flowing through the conduit or conduits of the inset body may then be substantially higher, for any given strength of the walls of the inset body, than would be practical in the absence of a substantial pressure at the exterior of the inset body.

The coils may extend to the wall of the casing or, in order to compensate for unequal expansion, may end at some distance therefrom as is somewhat exaggerated in Fig. 1. Through the intermediate spaces impurities which by the centrifugal force of the spiral motion are thrown towards the wall of the casing, sink downwards and may be removed from the lower portion of the casing. To facilitate the separation and removal of the impurities the wall of the casing may be provided with grooved bulges running parallel with the intermediate spaces between the winding convolutions, as indicated at 25 in Fig. 4. Only one helical or spiral coil is shown in this figure. The said coil is made without a core. Moreover, there may be any number of coils in the same casing. The said grooves 25 in which the heavy impurities gather, may be provided with cleaning openings or blow-out pipes at suitable points.

As indicated in Fig. 3, inspection glasses 26 are provided where necessary, to permit observation of the interior of the exchanger.

It is to be noted that the invention is not limited to a particular shape or geometry of the heat exchanger and that it may be embodied in apparatus of other form than the illustrated embodiments in which the casing has a cylindrical shape, and the outer periphery of the coils lies in a cylindrical surface.

When heat is transferred from gases to a liquid, from exhaust gases or water vapor to water, for example, it is suitable to permit the gas or gases to pass outside of the convolutions of the pipe or

pipes and the liquid inside thereof. Further, the passage area of the external passage should preferably diminish in the flow direction of the gas corresponding about to the volume reduction of the gas caused by the fall of temperature. This can be obtained by suitable adjustment of the thickness and/or the pitch of the coils as shown in Fig. 5 or by changing the outer or inner diameter. Of course, the case will be the reverse if the heat absorbing medium the volume of which increases in the flow direction, passes around the coils. The main point is that the passage area decreases or increases according to the volume change of the medium in the flow direction.

Having now described my invention, what I claim as new and desire to secure by Letters Patent is:

A heat exchanger comprising a substantially cylindrical shell, a plurality of conduits within 20 said shell, each conduit being in the form of a substantially right helicoid and said helicoids being concentric and of equal size and pitch and the turns thereof being equally spaced from each other thereby forming a plurality of helicoidal 25 passageways of substantially uniform cross-sectional shape through said cylindrical shell, the cross-section of each conduit as cut by a plane through the axis of the cylinder being substantially rectangular and the dimension of said cross-section perpendicular to the axis of the cylinder being substantially equal to the radius of the cylindrical shell and at least several times the dimension of the cross-section of the conduit parallel to the axis of the cylindrical shell, means for 30 passing a fluid through said conduits and means for passing another fluid through said passageways.

LAURITZ BENEDICTUS SCHIBBYE.
